UNITED STATES PATENT OFFICE.

OSCAR H. PIEPER AND ALPHONSE F. PIEPER, OF ROCHESTER, NEW YORK.

ADJUSTABLE CHAIR.

1,137,080.

Specification of Letters Patent. Patented Apr. 27, 1915.

Application filed April 21, 1913. Serial No. 762,503.

To all whom it may concern:

Be it known that we, OSCAR H. PIEPER and ALPHONSE F. PIEPER, both of Rochester, in the county of Monroe and State of New York, have invented certain new and useful Improvements in Adjustable Chairs; and we do hereby declare the following to be a full, clear, and exact description of the same, reference being had to the accompanying drawings, forming a part of this specification, and to the reference-numerals marked thereon.

Our invention has for its object to provide an adjustable chair of the general type in which the seat may be elevated and lowered on the base, such as, for instance, are employed by dentists and barbers, the purpose being to afford a construction with which the desired adjustments may be readily obtained, without requiring substantially any work on the part of the operator.

A further object of our improvements consists in affording a structure which permits the use of compressed air or other fluid pressure for raising the chair seat above the base, the application of pressure being controlled in a simple manner.

Another feature of the invention consists in the means which we employ for lowering the chair seat, and retarding the same at the limit of its downward movement so as to obviate a sudden shock or jar.

To these and other ends the invention consists in certain improvements and combinations of parts, all as will hereinafter be more fully described, the novel features being pointed out in the claims at the end of the specification.

In the drawings: Figure 1 is a vertical sectional view of a portion of a chair, showing the application of a preferred embodiment of the invention; Fig. 2 is an enlarged sectional view, with parts broken away, showing the controlling valve moved; Fig. 3 is a similar view, with the parts in another position, and Fig. 4 is a transverse section on the line 4^a—4^a of Fig. 1.

Similar reference numerals throughout the several figures indicate the same parts. In the embodiment disclosed, which is intended to be illustrative of one manner of carrying out the invention, 1 designates a chair base or pedestal, to which is attached the support 2, and within the latter is arranged a suitable casting embodying a cylinder 3 and a liquid chamber 4.

5 is a seat support upon which is mounted the seat of the chair, which it is unnecessary to show in the present drawing, the seat support being conveniently secured to the piston rod 6 which carries a piston 7, the latter being arranged for movement within the cylinder 3. The bottom of the cylinder 3 is connected with the liquid chamber by means of the passage 8 which is normally closed by a spring actuated valve 9 co-operating with a valve seat 10 formed in the removable casing 11. The valve 9 is arranged on a valve stem 12 which projects vertically through the casting and beyond the stuffing box 13 for a purpose that will appear hereinafter, and 14 is a spring arranged between the collar 15 and the shoulder 16 in order to hold the valve normally closed as shown. The chamber 4 is adapted to receive a heavy liquid, such as oil, which, when sufficient pressure is applied to the surface thereof, opens the valve 9 and is forced against the lower surface of the piston 7, so as to elevate the piston rod and seat support. The fluid 20 in the chamber 4 is forced into the cylinder under sufficient pressure to elevate the piston, and to this end there is provided a fluid pressure supply pipe 16 to which fluid is supplied under pressure from any suitable source, compressed air being preferably used. The pressure supply pipe 16 connects with the head 17 which is removably secured

in the casting, and is provided with a passage 18 extending vertically therethrough, 25 by which the fluid pressure is transmitted to the liquid chamber. At the base of the head, there is provided a distributor and separator 19 embodying a funnel shaped receiver 20, and a conical deflector 21 surrounded by a plurality of openings 22. The conical deflector 21 is disposed in vertical alignment with the receiver 20, so that the pressure fluid is distributed around the deflector and caused to enter the liquid chamber in an annular path, striking the liquid at a plurality of points, while the deflector also serves the further purpose of separating the liquid from the air when exhaust is taking place from the liquid chamber, and preventing the liquid from being drawn up into the passage 18 when the exhaust valve is open.

The head 17 is provided with a three-way valve 23 to which is connected a handle 24 by which the valve may be manually operated to admit the fluid pressure and to ex-

haust the pressure from the liquid chamber, as will be described presently. The head 17 is provided at its top with a muffler or exhaust chamber comprising a plurality of concentrically arranged annular walls 25 provided with openings 26 arranged alternately at the top and bottom thereof respectively. The muffler or exhaust chamber is connected with the atmosphere, and is closed at the top by a cover 27.

28 is an exhaust valve arranged on a seat in the head 17, and controlled by the spring 29. The stem of the valve and the spring are housed in a tube 30, the spring being held in place by a follower 31 which has threaded engagement with the adjusting screw 32. A squared head 33 is provided at the upper end of the screw 32, to permit of its adjustment, in order to vary the tension of the spring 29, which ordinarily is such as to permit the valve to open under the weight of the chair seat and the occupant, and to hold the valve closed when the chair is unoccupied. When the valve is in the position shown in Fig. 1, pressure is being admitted to the liquid chamber, to lift the piston 7, and when the valve is turned to the position shown in Fig. 3, the supply pipe is cut off, and communication is established with the atmosphere from the liquid chamber, through exhaust valve 28 and the exhaust chamber.

It is desirable to provide means for automatically shutting off the flow of the pressure fluid when the chair seat has reached a certain predetermined elevation, and to this end, we provide means for automatically operating the valve 23. For this purpose, a connecting rod 42 is pivoted to the valve 23, 40 and is in turn connected to an arm 44 which is pivotally mounted at 45 upon the cylinder head 46.

47 is a pin slidably arranged in the cylinder head 46 and in engagement with the arm 44.

The movement of the pin 47 would not be sufficient to impart an entire quarter turn to the valve, and in order to effect this additional movement, there is provided a spring actuated plunger 49, movable in bearings mounted on the cylinder head, and controlled by the spring 50. The plunger 49 carries a roller 51 which is arranged to engage a cam surface 52 on the arm 44. 55 Adjacent to the cam surface 52, is a substantially perpendicular surface 53, which is normally engaged by the roller 51, the plunger being forced toward said surface by the spring 50, and when the piston 7 reaches the top of the cylinder, the pin 47 raises the arm 44 far enough to bring the cam surface 52 into engagement with the roller 51, whereupon the spring actuated plunger acts to move the connecting rod 42 upwardly far enough to turn the valve the

required distance. By this means, when the piston 7 reaches the upper end of the cylinder, it effects closing of the valve 23 against further admission of pressure fluid, and exhausts the pressure in the liquid chamber. 70 While the chair seat is elevated, the fluid is held in the cylinder by the valve 9, and when it is desired to lower the seat, the lever 48 is operated to depress the valve stem 12 and the valve 9, permitting the liquid to flow back into the liquid chamber and the piston 7 to fall under the influence of the weight of the parts. As the piston descends, the air in the liquid chamber which is displaced by liquid flowing from the cylinder is forced out through the exhaust valve 28, but as the piston approaches the bottom of the cylinder, the seat support 5 contacts with the upper end of the rod 54 forcing it downwardly, and raising the 85 lever 48, to release the valve 9. This stops the out-flow of liquid from the cylinder, and produces a cushion for the piston, to take up the jar which would otherwise be produced when it reaches the bottom of the cylinder. 90 The arrangement of the annular walls in the muffler serve to gradually reduce the pressure of the fluid so as to prevent hissing or other annoying sounds as the air under pressure rushes from the liquid chamber to the atmosphere. 95

While the present application includes a particular embodiment of the invention, it is to be understood that we are not limited to the precise construction and arrangement 100 described, for the intention is to cover any changes or modifications that may come within the scope of the invention and the terms of the claims hereinafter.

We claim as our invention: 105

1. In an adjustable chair, the combination with a cylinder, of a piston movable within the cylinder, a liquid chamber in communication with the cylinder, a fluid pressure supply pipe communicating with the liquid chamber, a spring actuated valve controlling the passage of liquid to the cylinder, means for opening said valve, and means controlled by the downward movement of the piston for releasing said valve to permit it to close.

2. In an adjustable chair, the combination with a cylinder, of a piston movable within the cylinder, a fluid pressure supply pipe in communication with the cylinder, an exhaust for the fluid pressure, a spring actuated valve controlling the passage of liquid to the cylinder, means for opening said valve, and means controlled by the downward movement of the piston for releasing said valve to permit it to close.

3. In an adjustable chair, the combination with a cylinder, of a piston movable in the cylinder, a liquid chamber communicating with the cylinder, an exhaust outlet in com-

munication with the liquid chamber, a spring actuated valve for closing the passage from the liquid chamber to the exhaust outlet, and means actuated by the piston on its downward movement for retarding the flow of liquid from the cylinder.

4. In an adjustable chair, the combination with a cylinder, of a piston movable within the cylinder, a liquid chamber in communication with the cylinder, a fluid pressure supply pipe communicating with the liquid chamber, a valve controlling the supply of fluid pressure, and spring controlled means operating to close said valve, the spring controlled means being normally out of operative relation with the valve and automatically connected therewith at the limit of the upward movement of the piston.

5. In an adjustable chair, the combination with a cylinder, of a piston movable within the cylinder, a liquid chamber in communication with the cylinder, a fluid pressure

supply pipe communicating with the liquid chamber, a valve controlling the supply of fluid pressure, automatic means for throwing the valve from open to closed position, and devices for permitting the automatic means to operate at the limit of the upward movement of the piston.

6. In an adjustable chair, the combination with a cylinder, of a piston movable within the cylinder, a liquid chamber in communication with the cylinder, a fluid pressure supply pipe communicating with the liquid chamber, a valve controlling the passage of liquid to the cylinder, means for opening said valve and automatically controlled means for effecting closing of the valve during the downward movement of the piston.
